US00D600234S

(12) **United States Design Patent**
Suzuki

(10) **Patent No.:** **US D600,234 S**
(45) **Date of Patent:** **** Sep. 15, 2009**

(54) **SPEAKER**

(75) Inventor: **Satoshi Suzuki**, Tokyo (JP)

(73) Assignee: **Sony Corporation**, Tokyo (JP)

(**) Term: **14 Years**

(21) Appl. No.: **29/309,727**

(22) Filed: **Sep. 30, 2008**

(30) **Foreign Application Priority Data**

Jun. 20, 2008 (JP) D2008-015852
Jun. 20, 2008 (JP) D2008-015907

(51) **LOC (9) Cl.** **14-01**

(52) **U.S. Cl.** **D14/214**

(58) **Field of Classification Search** D14/204,

(57) **CLAIM**

The ornamental design for a speaker, as shown and described.

DESCRIPTION

FIG. 1 is a perspective view of a speaker showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view thereof, showing a line 9—9; and,

FIG. 9 is an enlarged partial view taken along a line 9—9 of FIG. 8.

The das-dot lines which define the bounds of the claimed design form no part thereof.
